 Emhart Manufacturing Company, a corpora-
 tion of Delaware

Application October 29, 1947, Serial No. 782,754

4 Claims. (Cl. 158—112)

1

This invention relates to improvements in flame arrestors and it consists in the combinations, constructions and arrangements herein described and claimed.

An object of the invention is to provide a flame arrestor which will be effective to arrest flame close to a burner nozzle when conditions arise which tend to cause such a flame to flash back from the burner nozzle in a gaseous fuel supply line.

A further object of the invention is to provide a flame arrestor of a unitary character which is adapted to be operatively positioned in a gaseous fuel supply line close to a burner nozzle that is being supplied with gaseous fuel by that line so as to prevent flash back of flame in the line without offering any substantial obstruction to the flow of the gaseous fuel to the nozzle.

A further and more specific object of the invention is to provide a flame arrestor having a core formed to provide numerous small passages extending therethrough and positioned in a gaseous fuel line as close to a burner nozzle that is being supplied with gaseous fuel from that line as is physically possible without causing any serious restriction of flow of gaseous fuel from the core passages into the burner nozzle.

To attain the foregoing and other objects of the invention, a straight section of a gaseous fuel supply pipe containing our arrestor and a holder for a burner nozzle to be served by that fuel supply pipe may be combined so that the volume of a space that is provided between the downstream end of the arrestor core and the burner nozzle as required to allow desirable uniformity of flow of gaseous fuel from the core passages into the rear of the nozzle is kept to a minimum. This space is kept as small as possible so as to keep to a minimum the volume of fuel mixture which may explode therein when a flash back occurs and hence similarly to restrict the force and velocity tending to drive the flame back through the arrestor. A second important advantage of the structure which provides a space of minimum volume between the burner nozzle and the downstream end of the arrestor core is that flow of burnt gases resulting from a flash back and burning of gaseous fuel-air mixture on the downstream end of the arrestor core out through the nozzle is at a rate very much reduced from the normal for any given mixture pressure in the supply line, this because of the high temperature and volume of the burnt gases in this restricted space. Rate of flow and rate of release of heat from the burnt gases are so re-

2

duced that burning can occur on the downstream end of the arrestor core for many hours without damage to the equipment. In all installations containing flame arrestors of the prior art of which we have any knowledge, burnt gases resulting from a flash back have flow space in which to cool substantially before arriving at the nozzle and flow through the nozzle hence is not reduced in the manner or to the extent provided by our invention.

Other objects and advantages of the invention hereinafter will be pointed out or will be obvious from the following description of a practical embodiment of the invention, as shown in the accompanying drawings, in which:

Fig. 1 is a view, mainly in vertical section and partly in side elevation, of a burner nozzle and its gaseous fuel supply line operatively applied to a burner block and equipped with the novel flame arrestor of the present invention; and

Fig. 2 is a relatively enlarged, partial transverse section of the core of the flame arrestor, substantially along the line 2—2 of Fig. 1.

In Fig. 1, numeral 1 designates a refractory burner block which is provided with a burner port 2 having its outer end portion enlarged or counterbored as indicated at 2a to accommodate the inner end and part of the length of a burner nozzle 3. The burner block 1 is shown as being provided with an outer metallic face plate 4 uprising from a horizontal supporting plate 5 which in turn extends across and rests upon a vertically disposed supporting plate 6, the inner end portion, designated 5a of the plate 5, underlying an outer end portion 7 of the lower surface of the burner block. The parts 4, 5 and 6 may constitute part of a metallic framework or casing of the furnace (not shown) or other heat-using structure of which the burner block 1 is a part.

The burner nozzle 3 is mounted in a holder 8 which is shown as being an internally threaded metallic ring surrounding the outer end portion of the nozzle, designated 3a, which is relatively enlarged and is screw threaded externally so that it may be screwed into the holder 8 until a sealing gasket 9 surrounding the outwardly projecting portion of the burner nozzle is compressed by a flange 10 on the outer end of the nozzle against the outer face of the nozzle holding ring 8. The nozzle 3 may have a screwdriver slot 10a in its flanged outer end to facilitate mounting of the nozzle in its holder 8 or removal therefrom.

The nozzle holding ring 8 is located at the inner end of and is rigid with a straight tubular

end section or length of pipe 11 of a gaseous fuel supply line. In the example shown, the nozzle holding ring 8 is welded, as at 8a, to the inner end of the tubular fuel supply line section 11 although it might be integral therewith or might be simply clamped rigidly in place between the inner end of the tubular section 11 and the plate 4 in concentric relation to the outer part of the port 2 in the burner block. The arrangement is such as to support the nozzle 3 as a concentric projection beyond the inner end of the supply line section 11 so that the nozzle 3, the holder 8 and the fuel supply line section 11 may all be removed as a unit from the burner block 1 when this is desired for any useful purpose. In the example shown, the outer end of the supply line section 11 is operatively connected, as by screw threaded engagement at 12, with one of the nipple portions, designated 13, of a T-fitting 14. This T-fitting has a nipple portion 15 opposite the nipple portion 13 into which a removable plug 16 is screwed. The T-fitting has its third nipple portion, designated 17, operatively connected with another tubular section, or pipe, designated 18, of the gaseous fuel supply line. The section 11 of the fuel supply line rests upon upwardly projecting, adjustable jackscrews 19, carried by the horizontal supporting plate 5, being clamped in place in relation to the burner block face plate 4 and to the jackscrews 19 by a U-bolt 20, the legs of which extend through holes, such as that indicated at 21, in the horizontal supporting plate 5 and are engaged beneath that plate by suitable fastening means, such as the washer 22 and the nut 23.

The assembly which has been described so far is conventional, comprising any suitable known or preferred burner nozzle, its supporting means and its gaseous fuel supply means, the burner nozzle being operatively applied to a burner block. These parts, per se, do not form part of the present invention and, of course, may vary widely in details from those shown in the drawings and hereinbefore particularly described. The novel flame arrestor of the present invention comprises a tubular shell or casing 24 which fits slidably in the tubular section 11 of the fuel supply line. As shown, the tubular shell or casing 24 is slightly longer than the section 11 of the fuel supply line but its length may vary from that shown. Within the shell or casing 24 is a core comprising elements which will now be particularly pointed out. One of these is a fixed, rear retaining element 25 which is disposed diametrically of the shell 24 adjacent to its outer end. As appears from Figs. 1 and 2, considered together, the element 25 may consist of a strip of metal or other suitable material positioned vertically in the tubular shell 24 with its edges turned fore-and-aft and made fast to the shell, as by having upper and lower end portions, designated 25a, bent laterally in opposite directions against the inner peripheral wall of the shell 24 and fastened to the latter by rivets, one of which is indicated at 26 in Fig. 1. The strip 25 may have a straight rearward edge 27 and a concavely curved front edge 28. An intermediate portion of such strip extends through a vertical slot 29 in an axial stem 30 of the flame arrestor core. A cross pin 31 may be used to fasten the strip and the stem together.

The stem 30, which is shown as being a solid rod but which might be hollow if plugged or formed so as to prevent flow of fuel-air mixture through it, is of sufficient length to extend rear-

wardly from the shell 24 into the T-fitting 14 when the forward end portion of the stem is located in the shell 24 a short distance to the rear of the outer end of the nozzle 3, where it is attached to a front retaining element, designated 32. This front retaining element comprises a strip of metal or other suitable material of sufficient length to contact at its opposite ends with diametrically opposite portions of the inner peripheral wall of the shell 24 when the intermediate portion of the strip is fastened to the forward end of the stem 30. In the example shown, the forward end of the stem 30 has a diametrically extending slot therein, as indicated at 33, to accommodate the intermediate portion of the retaining strip 32, the latter being fastened to the slotted end portion of the stem 30 by a pin 34. The strip 32 is shown as having a straight forward edge 35 and a convexly curved rear edge 36. This straight forward edge 35 of the retaining strip is spaced from the outer end of the nozzle 3 by a small space indicated at 37 when the shell 24 has been pressed against the outer face of the nozzle holding ring 8. Some of the reasons for and advantages of keeping the size of the space 37 at a minimum have been generally explained. Further advantages of the specific structure will later be pointed out. In the example shown, this position of the shell 24 is maintained by the action of a coil spring 38 which is disposed between the outer straight edge 27 of the rear retainer 25 and the plug 16 in the remote nipple portion 15 of the T-fitting 14, the spring 38 then being under sufficient compression to prevent accidental rearward movement of the shell 24 in the tubular member 11.

In addition to the elements just described the core of the flame arrestor compresses a filler, generally designated 39, for the space within the shell 24 extending radially from the inner wall of the latter to the stem 30 and longitudinally between the rear and front retaining elements 25 and 32, respectively. The filler 39 is foraminous in character. As shown in part in Fig. 2, it may be formed of plain and longitudinally corrugated light gauge filler strips 40 and 41, respectively, extending in alternating, closely packed convolutions or turns about the stem 30, whereby to provide a multitude of longitudinally extending passages 42 in the filler. These filler strips and hence the walls of the longitudinal passages in the filler may be aluminum or any other suitable material having good heat conducting properties and sufficiently resistant to the heat which may be encountered in service. The passages 42 shown in Fig. 2, having their defining walls formed of portions of continuous alternating plain and corrugated sheets as above described, will extract heat from gases therein rapidly and in a highly efficient manner. The filler passages may be formed with individual walls, as conventional tubes, or in any other known way, and may have cross-sectional configurations varying widely from those shown. The filler 39 may have its rearward end curved concavely as indicated at 43 and its front end curved concavely as indicated at 44, Fig. 1, to conform to the concave curvature of the forward edge 28 of the rear retainer 25 and the convex curvature of the rear edge 36 of the front retainer 32, respectively.

In operation, gaseous fuel may pass through the filler passages of the flame arrestor to the burner nozzle. Should conditions change from the normal so as to cause flame to flash back

from the nozzle, the flame arrestor will restrict any flame at the rear of the nozzle to the downstream end of the arrestor when the gas to air ratio of the gaseous fuel mixture and the gaseous mixture pressure are within any ranges that are likely to be encountered in service. Experiments have shown that at loads requiring a burner pressure in excess of 0.05 inch water gauge, the flame would be retained indefinitely on the discharge side of the arrestor core. On several occasions, conditions have been such as to cause or allow flame to flash back through the burner nozzle in an installation like that shown in Fig. 1 and, in each case, the flame has been retained on the arrestor. On one occasion, it burned over a whole week end on the arrestor with no damage or back fire.

The space 37 between the downstream end of the arrestor core and the outer end of the burner nozzle confines any explosive force to less than enough to force the flame back through the arrestor faster than the arrestor can extract heat from the burning gas. The volume of the space between the arrestor core and the burner nozzle influences directly both the quantity of heat that must be absorbed by the arrestor and the pressure developed which in turn influences the velocity with which the hot gas is driven back through the arrestor. It is important that the size of this space be kept to a minimum consistent with maintaining the required uniformity of flow from the arrestor core passages into the burner nozzle. The concave curvature of the front end 44 of the arrestor core contributes to this result as the discharge ends of the core passages are thus located nearer to the inlet end of the burner nozzle as they are farther from the axial line of the core and burner nozzle. There is also the relation of the volume of the space to the cross-sectional area of the burner nozzle passage to be considered. In trial equipment embodying the invention substantially as hereinbefore particularly described, the space 37 had a volume of approximately 1.8 cu. inches and the free cross-sectional area or exhaust area of the nozzle was approximately 0.3 sq. inch, the ratio of these parts thus being approximately 6 to 1. The core was approximately 6 inches long. This trial equipment was operated with advantageous results such as have in part been hereinbefore described. When the core was moved back from the burner an inch or more, thereby enlarging the intervening space, the effectiveness of the flame arrestor was markedly reduced. Also, when the length of the arrestor was reduced to approximately 4 inches, the effectiveness of the device was reduced somewhat although some of the advantages of the invention as hereinbefore described were still retained. These dimensions of parts are given by way of examples and not as limitations on the invention as obviously component parts having various dimensions and proportions may be used in constructing and using flame arresting equipment without departing from the spirit and scope of our invention.

We do not wish to be limited to the details of the illustrative embodiment of the invention as many changes therein and modifications of such embodiment will now be obvious to or readily occur to those skilled in the art.

We claim:

1. A unitary flame arrestor for a burner assembly comprising a burner nozzle, a gaseous fuel supply line including a straight tubular final

section next to the nozzle and a nozzle holding ring connecting the nozzle operatively with the adjacent end of the straight tubular final section and projecting radially inward beyond the latter, said arrestor comprising a tubular casing slidable in the straight tubular final section of the fuel supply line against the inwardly projecting portion of the holding ring, an axial stem within the casing and projecting rearwardly therefrom in the fuel supply line, a filler in the casing between the latter and said stem, said filler terminating rearwardly of the forward end of the casing and comprising a multitude of longitudinal passages extending therethrough and distributed throughout the cross-sectional area of the filler, said passages having walls of good heat transmitting properties, diametrically disposed retainer strips in said casing at the opposite ends of said filler, said strips being fastened intermediately to the stem and the rear strip being fastened at its ends to the casing, a coil spring on the rearwardly projecting portion of the stem against the rear retainer strip, and removable means bearing on the spring to compress it against the rear retainer strip to yieldingly maintain the casing in place against the nozzle holding ring.

2. A flame arrestor for a burner assembly comprising a substantially straight tubular burner nozzle having only an axial bore for the passage of gaseous fuel therethrough and a gaseous fuel supply line including a straight tubular section having a bore of substantially uniform cross-section throughout its length and nozzle holding means at the downstream end of said tubular section supporting said nozzle in axially aligned cooperative relation to the tubular section, the bore of said tubular section being substantially larger in cross-section than the adjacent end of the bore of said nozzle, said arrestor comprising a core having a multitude of longitudinal passages extending therethrough so as to be distributed around the longitudinal axis and throughout the cross-section of the core, said core fitting in the bore of the supply line tubular section closely enough to prevent flow of gas between said core and the surrounding wall of said tubular section of the supply line so as to confine flow of gaseous fuel through the portion of the tubular section occupied by said core to the longitudinal passages of the core, said core being positioned in the supply line tubular section so as to leave a small space therein between the downstream end of the core and the adjacent end of the bore of the nozzle and being formed at its downstream end so that the downstream ends of the longitudinal passages therethrough are relatively nearer to or farther from the plane of the adjacent end of the nozzle bore as such passages are radially farther from or nearer to the axis of said core, respectively, so as to permit approximate uniformity of flow from the several passages of the core into the nozzle.

3. A flame arrestor for a burner assembly comprising, in combination, a gaseous fuel supply line including a straight tubular final section and a tubular nozzle secured to the downstream end of said final section so as to constitute a concentric relatively reduced extension thereof, the internal cross-sectional area of said final section of the supply line being substantially greater than the internal cross-sectional area of the adjacent end of the nozzle, a core comprising a multitude of longitudinally extending

passages distributed symmetrically around the longitudinal axis thereof, a tubular casing in which said core fits closely, said casing being positioned in said final section of the supply line so as to leave a relatively small space between the downstream end of the core and the adjacent end of the nozzle, said casing having a gas flow preventing fit with the surrounding wall of the final section of the supply line so that all gaseous fuel passing through said final section must pass through the longitudinal passages of said core to reach the relatively small space between the downstream end of the core and said nozzle, the downstream end of said core being concavely curved so that the distance of travel of gaseous fuel from the individual core passages through said small space into said nozzle is approximately the same for all core passages despite differences in their radial distance from the axis of the core.

4. A flame arrestor for a burner assembly comprising, in combination, a gaseous fuel supply line including a straight tubular final section and a tubular nozzle secured to the downstream end of said final section so as to constitute a concentric relatively reduced extension thereof, the internal cross-sectional area of said final section of the supply line being substantially greater than the internal cross-sectional area of the adjacent end of the nozzle, a core comprising a multitude of longitudinally extending passages distributed symmetrically around the longitudinal axis thereof, a tubular casing in which said core fits closely, said casing being positioned in said final section of the supply line so as to leave a relatively small space between

5 the downstream end of the core and the adjacent end of the nozzle, said casing having a gas flow preventing fit with the surrounding wall of the final section of the supply line so that all gaseous fuel passing through said final section must pass through the longitudinal passages of said core to reach the relatively small space between the downstream end of the core and said nozzle, said core also comprising an axial stem extending therethrough and retainer strips disposed diametrically of the core at the opposite ends thereof and fastened intermediately to said stem, the retainer strip at the upstream end of the core being fastened at its ends to the casing of said core and the retainer strip at the downstream end of the core being free at its ends from said casing.
